UNITED STATES PATENT OFFICE.

JAHN RAZNTCH, OF CLOQUET, MINNESOTA.

VENTILATING APPLIANCE.

1,140,609.

Specification of Letters Patent.

Patented May 25, 1915.

Application filed June 4, 1914. Serial No. 843,038.

To all whom it may concern:

Be it known that I, JAHN RAZNTCH, citizen of the United States, residing at Cloquet, in the county of Carlton and State of Minnesota, have invented certain new and useful Improvements in Ventilating Appliances; and I do declare the following to be a full, clear, and exact description of the invention, such as will enable others skilled in the art 10 to which it appertains to make and use the same.

This invention relates to new and useful improvements in ventilating devices and more particularly to a ventilator applicable 15 to the wall of a room and the primary object of the invention is to provide a device of this character which may be readily operated at will to permit bad air in the room to be removed therefrom and fresh air to be 20 circulated.

A further object of this invention resides in providing a casing of cylindrical design adapted to be mounted in the wall and having hinged closures for its ends which are 25 normally held closed.

Still another object resides in providing a connection between the closures for the casing whereby when one is opened the other will be opened and both of which are 30 normally held closed under spring tension.

Still another object resides in providing a device which is simple and durable in construction, inexpensive to manufacture and one which will be very efficient and useful 35 in operation.

With these and other objects in view my invention consists in the novel features of construction, combination and arrangement of parts as will be hereinafter referred to 40 and more particularly pointed out in the specification and claims.

In the accompanying drawing forming a part of this application: Figure 1 is a longitudinal section through a device constructed 45 in accordance with my invention and applied to use in the wall of a structure, the ends of the device being shown open: Fig. 2 is a longitudinal section through the device, as seen on line 2-2, Fig. 3: Fig. 3 is an end elevation of the device: Fig. 4 is a section therethrough as seen on line 4-4, Fig. 1. Fig. 5 is a section as seen on line 5-5, Fig. 1.

In describing the invention I shall refer 50 to the drawing in which similar reference characters designate corresponding parts

throughout the several views and in which 1 indicates the cylindrical casing or housing mounted in the wall of a structure so that one end of the same communicates with the 60 interior thereof while the other end communicates with the exterior. Extending diametrically across the casing or housing 1 at the ends thereof are the bars 2 the centers of which are provided with bearing 65 boxes 3 for receiving the ends of the rotatable and longitudinal shaft 4 therein. Mounted at predetermined points on the shaft 4 in spaced relation to one another are a pair of fans 5 which are provided 70 with a plurality of blades or vanes 6, the latter being twisted for obvious purposes, as clearly disclosed in the drawing.

Formed on or otherwise secured to each end of the cylindrical casing 1 is a peripheral and laterally extending flange 7 and hinged to the flanges 7 are the oppositely operating closures 8 and 9. A spring member 10 is arranged in connection with each of the hinges for said closures 8 and 9 so as 80 to normally retain the latter over the open ends of the body or casing and I have provided a means whereby when one closure is disposed to its open position the other will likewise be so disposed. 85

The closure 8 may be said to be the one at the inner end of the housing or casing, that is the one disposed in the interior of the structure and engaged with the outer face thereof is a flexible connection 11 the 90 free end of which is provided with a ring or the like 12 whereby the same may be readily engaged when desired. Engaged with the inner face of the closure 8 adjacent its hinged end is an additional flexible 95 connection 13 which is directed over a roller 14 at the adjacent end of the adjacent bar 2. This flexible connection is guided longitudinally along the inner face of the wall of the body or casing 1 and trained over an 100 additional roller 15 at one end of the bar 2 adjacent the opposite end of the casing or housing 1. An arcuate projection 16 is provided on the hinged end of the closure 9 which depends below the hinge proper 105 thereof and loosely connected with this projection is a link 17 with which the opposite end of said flexible connection 13 is engaged. As stated above, these closures 8 and 9 are normally held in their effective 110 closed positions over the ends of the body 1 by means of the spring 10 but it will be seen

from the above description of the construction of the connecting means between said closures that upon the opening of the closure 8 by drawing upon the flexible connection 11, a pull will be exerted upon the curved extension 16 at the hinged end of the closure 9, thus causing the latter to be disposed to its open position. Under normal conditions, these closures 8 and 9 are disposed to their closed positions over the ends of said body 1 so that dust, dirt and all extraneous matter will be excluded from the body 1 and from the interior of the structure but upon the opening of the closure 8, as stated above, the closure 9 will be also opened and the foul air permitted to pass from the structure as will be readily understood.

From the above description of the construction of my improved device the operation thereof and the manner of applying the same to use will be readily understood, and it will be seen that I have provided a device which is simple and durable in construction, inexpensive to manufacture and one which will be very efficient and useful in operation.

While I have particularly described the elements best adapted to perform the functions set forth, it is obvious that various changes in form, proportion and in the minor details of construction may be resorted to, within the scope of the appended claims, without departing from the spirit or sacrificing any of the principles of the invention.

Having thus described my invention, what I claim is:

1. A ventilator of the character described comprising a tubular casing, a bar at each extremity of said casing coincident with the vertical axis thereof, an outwardly opening

closure hingedly connected to each extremity of said casing, spring means in connection with said closure to retain the latter over the extremities of said casing, a flexible member connected at one end to one of said closures and extending longitudinally of said casing, means at the lower extremities of said bars for co-operation with said member to guide the same, and a clip at the hinged end of the remaining closure for engagement with the free end of said member whereby said closures may be simultaneously opened substantially as and for the purpose set forth.

2. A ventilator of the character described comprising a tubular casing, a bar at each end of said casing coincident with the vertical axis thereof, an outwardly opening closure hingedly connected at each extremity of said casing, spring means in connection with said closures to normally retain the latter over the extremities of said casing, a flexible member connected at one end to the inner surface of one of said closures and extending longitudinally of said casing, a guide roller at the lower extremity of each of said bars over which said member is directed, a downwardly depending extension disposed contiguous to the hinged edge of the remaining closure and connected to the free end of said member whereby said closures may be simultaneously operated substantially as and for the purpose set forth.

In testimony whereof I have hereunto set my hand in presence of two subscribing witnesses.

JAHN RAZNTCH.
